tion of Indiana

Application October 16, 1943, Serial No. 506,563

6 Claims. (Cl. 93—3)

1

This invention relates to packaging of materials in their powdered or comminuted form, and has to do with means for and a method of accomplishing such packaging.

There are various materials which, in use, are dissolved in powder form, in water or other solvent. Many of these materials, such, for example, as effervescent substances, rapidly deteriorate when exposed to moisture or to the atmosphere. It is desirable, therefore, that such materials be enclosed in air and moisture proof containers of a character to protect them against deterioration. Packaging such materials in powder form frequently is difficult, time consuming, and results in considerable loss of the material being packaged, all of which materially increases the cost of the material in its packaged form.

I have found that a material saving in time, as well as in the size of the package containing a predetermined amount of a given material, originally in powder form, and in the material wasted in the packaging operations, can be effected by compacting the powdered material into tablet form, sealing the tablets in containers or envelopes formed of protective material effective for excluding air and moisture from the envelope, and then crushing the tablets in the sealed envelope so as to reduce them to powder form. While in certain instances satisfactory results may be attained by crushing the tablets only sufficiently to cause breakage of the bond between the particles of the tablet, so that the resulting powder is considerably denser than the original powder from which the tablet was formed, and occupies but little more space in the container or envelope than the tablet occupied, in other cases it is desirable that the tablet be crushed more finely to assure rapid dissolving of the material in the water or other solvent to which it is added. In the crushing of the tablet to the latter extent, the bulk of the resultant powder is materially greater than that of the tablet and, unless proper precautions are taken, there is risk that the enclosing envelope or package may be ruptured or rendered permeable to air and moisture by the interior pressure exerted thereon in the crushing operation. That is particularly true when the packaged tablets are crushed by means of crushing rolls exerting pressure upon the tablets starting at one side thereof and progressing thereacross to the opposite side, which method of crushing is particularly desirable as rendering possible high speed operation with resulting increased production. An important feature of my invention is the provision of means

2

whereby the packaged tablets may be crushed in the manner stated without risk of injury to or impairment of the efficiency of the protecting container or envelope.

Coffee extract may be taken as another example of a material which may be packaged to particular advantage by the means and the method of my invention. Coffee in beverage form is used in large quantity by our military forces, many of whom are located in tropical and semi-tropical countries characterized by high temperatures and high humidity. It often is difficult to brew coffee in the field and supply it to men engaged in maneuvers. In order to meet that difficulty it has been proposed to prepare a powdered coffee extract by first preparing a brew or liquid extract which is then evaporated to a solid by the use of low pressure evaporation, or spray drying. The solid material thus obtained may be granulated to a relatively fine powder by the use of a suitable solvent and evaporating procedure. The resultant powder rapidly hardens and deteriorates, losing its flavor, if exposed to the air, and should be packaged in hermetically sealed containers with as little exposure to atmosphere as possible. In practicing my invention, a powder—coffee extract powder, for example—is compressed into tablets, in a known manner and by known means, each tablet containing a predetermined amount of the original powder and being of approximately one-fifth the volume of such predetermined amount of the original powder from which the tablet was formed. The tablets thus produced are self-sustaining to the extent that they may readily be handled and packaged without objectionable breakage, but the bond between the particles of the tablet is sufficiently slight so that such bond will be broken when the tablet is subjected to appreciable, but not great, pressure, causing separation of the particles and reducing the tablet to powder form, the resultant powder being denser than the original powder and occupying somewhat greater space than the tablet. Thereafter, the packaged powder may be, and preferably is, subjected to further crushing pressure effective for reducing the size of the particles of the powder, and thereby rendering it more readily soluble. That is desirable with respect to coffee extract in view of the fact that in many instances, when troops are in action in the field, hot water is not available and the extract has to be dissolved in cold water. Even in cases where hot water is available, it is often desirable that the coffee extract be dissolved in the water with a minimum of

delay, and in such cases also there is an advantage in subjecting the packaged powder to a further crushing operation. The crushing of the tablets and subsequent crushing of the packaged powder are performed by crushing rolls between which the packaged tablets and the packaged powder are passed, the crushing pressure exerted by these rolls progressing from one side of the package to the opposite thereof. The use of crushing rolls is desirable as being conducive to high speed operation, but there is risk that in the crushing operation, due to the greater bulk of the packaged powder relative to the tablets, the enclosing container or envelope may be subjected to internal pressure of such high value as to cause rupturing of the package or reduction in or destruction of its protective characteristics. In order to avoid that difficulty, in packaging the tablets I provide space thereabout for accommodating the powder to which the tablet is reduced, and, preliminary to the crushing of the tablet, break the tablet within the package into two portions and space those portions apart, providing at the central area of the package a space of appreciable extent between the portions of the broken tablet, such space serving to guard against subjecting the container or envelope to objectionably high interior pressure, during the operation of crushing the tablet, as will be explained more fully later.

Further objects and advantages of my invention will appear from the detail description.

In the drawings:

Figure 1 is a diagrammatic lengthwise vertical sectional view of a packaging machine embodying my invention;

Figure 2 is a plan view of a packaged tablet produced by the machine of Figure 1, showing the package in actual size and in the condition in which it is before the tablet is broken preliminary to crushing thereof;

Figure 3 is a sectional view, on an enlarged scale, taken substantially on line 3-3 of Figure 2, the tablet being shown in elevation;

Figure 4 is a fragmentary detail sectional view, on an enlarged scale, of the breaking rolls, with a packaged tablet, shown in elevation, passing between the rolls and being broken thereby;

Figure 5 is a plan view of the packaged tablet, in actual size, after completion of the breaking operation;

Figure 6 is a plan view of the package of powdered material which results from passage of the packaged broken tablet through the two sets of crushing rolls;

Figure 7 is a sectional view, on an enlarged scale, taken substantially on line 7-7 of Figure 6;

Figure 8 is a fragmentary side view of the packaging machine of my invention, showing the means for yieldingly urging the upper breaking roll toward the lower breaking roll; and

Figure 9 is a view like Figure 7, showing the means for yieldingly urging one of the upper crushing rolls toward the corresponding lower crushing roll.

The packaging machine shown diagrammatically in Figure 1 comprises a base member 10 upon which is suitably mounted an electrical vibrator 11 of known type. This vibrator is connected by a bracket 12 to a trough structure 13 supported by spring means 14 for lengthwise vibration, the structure 13 receiving, at its forward end, tablets *t* formed from compacted powdered material, as above referred to, from a trough 15 of a tableting machine (not shown).

At its rearward end the trough structure 13 delivers the tablets *t* to buckets 16 of a feeder 17. The buckets deposit the tablets upon the upper face of a strip 18 of a suitable thermobonding material drawn from a roll 19 thereof suitably mounted on a spindle 20, strip 18 passing upward through an opening 21 through base member 10, and thence over a guide roller 22, from which it passes downward and rearward generally concentrically with the lower end portion of the feeder 17. The strip 18 may be a strip of regenerated cellulose, or it may be a strip of any other suitable material provided with a coating of a suitable known substance which is thermobonding. A strip 23, similar to strip 18, is led from a roll 24, suitably mounted on a spindle 25, downward about a guide roller 26 and thence rearward. The strip 23 is thus disposed, rearward of guide roller 26, to overlie the tablets *t* deposited in spaced relation upon the upper face of strip 18 by the feeder 17.

The strips 18 and 23, with the tablets *t* between them, pass rearward from guide roller 26 between upper and lower sealing rolls 28 and 29, respectively. These rolls are heated, conveniently by means of electrical resistors, and maintained at proper sealing temperature, in a known manner. Each of the rolls 28 and 29 is provided with a plurality of—in this case, four—recesses 30 of generally square shape and of somewhat greater width than the tablets *t*, of proper depth to receive, when two of the recesses 30 are in opposed relation, the tablets disposed between the strips 23 and 18 without subjecting the tablet to pressure. The strips 23 and 18 are each of somewhat greater width than the recesses 30, and the areas of the rolls 28 and 29, beyond the recesses 30 thereof, are oppositely threaded. In the passage of the strips and the tablets between the rolls 28 and 29, the strips are drawn over the tablets and are sealed together by the rolls 28 and 29, the threads of the latter corrugating the outer marginal portions of the strips beyond the tablet and also corrugating the portions of the strips between successive tablets. In that manner the tablets are sealed in protective containers or envelopes individual thereto and connected together in spaced relation so as to form a string of packaged tablets, it being understood that the material of the strips 23 and 18 is of a character to protect the enclosed tablets from the air and, to a considerable extent, from moisture.

The string of tablets passes rearward from the rolls 28 and 29 between upper and lower guide rollers 31 and 32. A strip of metal foil 33, preferably aluminum foil, though lead foil or any other suitable membrane may be used, passes from a roll 34, mounted on a spindle 35, about guide roller 31 and thence rearward in overlying relation to the string of packaged tablets. A second strip 36 of metal foil passes from a roll 37, mounted on a spindle 38, upwardly through an opening 39 in base member 10, and thence over roller 32 and rearward in underlying relation to the string of packaged tablets. The strips 33 and 36, together with the string of packaged tablets, pass rearwardly between a second pair of sealing rolls comprising an upper roll 41 and a lower roll 42, these rolls being similar to the first pair of sealing rolls 28 and 29. The opposed surfaces of the strips 33 and 36, as they pass between the rolls 41 and 42, are coated with a suitable known thermobonding substance. The rolls 41 and 42 stretch the metal foil strips over the packaged tablets and seal the lateral mar-

ginal portions of these strips, as well as the portions thereof lying between the packaged tablets, together and to the strips 23 and 18 so as to bond all of the strips together and provide an air and moisture tight seal therebetween. In that manner, each of the tablets is enclosed within an envelope comprising the inner strips 23 and 18 of regenerated cellulose or other suitable material, and the outer metal foil strips 33 and 36.

In Figures 2 and 3 I have shown one of the packaged tablets produced in the above manner. The tablet *t* preferably is in the form of a flat-sided disc, as shown, but within the broader aspects of my invention may be of any other suitable form. This tablet is enclosed within the envelope comprising the strips 18 and 23, and 33 and 36, the strips 18 and 23 and the strips 33 and 36 converging outward of the tablet *t* and enclosing within the envelope a space 45 of outwardly tapering or conical cross section extending peripherally about the tablet *t*. The marginal portions of the strips extending outward beyond the space 45 are corrugated and sealed together at 46, as above explained, and are disposed substantially in the median plane of the packaged tablet. The corrugations of the marginal portions of the package are produced by the threads on the sealing rolls, above referred to, these threads also serving to grip the lateral marginal portions of the strips so as to feed the latter and the string of packaged tablets rearward between the pairs of sealing rolls, as will be readily understood, it being understood that the rolls of the strips may have associated therewith suitable means for preventing overrunning thereof and for maintaining the strips under proper tension as they are drawn from the rolls thereof, in a known manner.

From the sealing rolls 41 and 42, the string of packaged tablets passes rearward to a pair of breaking rolls 47 and 48. Each of these rolls is provided, at each end thereof, with a bearing rail or ring 49 which contacts the corresponding bearing ring of the other roll and cooperates therewith for positively limiting movement of the rolls 47 and 48 toward each other, one of the rolls—preferably the upper roll 47—being yieldingly urged toward the lower roll 48 in a suitable known manner. In Figure 8 I have shown means 70, comprising a compression spring 71 and associated parts, similar to that of Patent No. 2,424,103, for yieldingly urging roll 47 toward roll 48. Any suitable known means may be employed for that purpose.

Each of the breaking rolls 47 and 48 is provided with a plurality of—in this case, four—breaking bars 50 suitably mounted thereon and extending lengthwise thereof. The respective breaking bars 50 comprise a breaking portion 51 of somewhat greater extent lengthwise of the roll than the width of the packaged tablet *t*, so as to extend throughout the full width of the latter during the breaking operation. The breaking portion 51 has a following face 52 disposed substantially radially of the associated roll, and a leading face 53 inclined outwardly of the roll toward the following face 52, the outer ends of faces 52 and 53 being connected by a relatively narrow flattened face 54 the corners of which preferably are slightly rounded. The breaking bars 50 of the rolls 47 and 48 are equally spaced about the respective rolls and are so disposed that the bars of one roll are brought into opposing relation to those of the other roll, during rotation of the

rolls, with the opposed bars disposed to engage the central areas of the packaged tablets as the packages *p* pass between the rolls. When the breaker bars 50 are disposed in opposed relation, the bite therebetween is appreciably less than the thickness of the packaged tablets *t*. The tablet is thus subjected to pressure between the breaking surfaces 54 of portion 51 of the bars 50, as shown more clearly in Figure 4. The packaged tablet 10 is thus broken into two portions *t*1 and *t*2, and the latter portion of the broken tablet is moved, by the inclined leading surfaces 53 of the breaking bars, rearward within the envelope or package *p*, while the forward portion *t*1 of the broken tablet 15 remains substantially undisturbed. In that manner, the packaged tablet is broken into a following portion *t*1 and a leading portion *t*2, and the latter portion is moved rearward within the package so as to be separated from the following portion *t*1 by a space 55 of appreciable width and 20 volume therebetween. During this breaking operation, the outer or nose portions of the breaking bars press into the package *p* from opposite sides thereof, and subject the tablet to breaking pressure along a transverse line substantially perpendicular to the direction of travel of the package *p*, the inwardly diverging walls of the package, defining the space 45, providing a certain amount of slack in the package permitting inward movement of the central areas of the top and bottom walls thereof, with the nose portions of the breaking bars, without subjecting the package to injurious stresses. The package *p*, as it passes 25 rearward from the breaking rolls, contains the broken tablets now separated into a following portion *t*1 and a leading portion *t*2, the latter portion having been shifted toward the leading side of the package, these two portions being separated by the space 55 therebetween, and the 30 package, at the top and the bottom thereof, having its central portion forced inwardly a short distance to provide a transverse trough or depression 56, as shown more clearly in Figure 5.

The string of packages *p* passes from the breaking rolls 47 and 48 rearward between a first pair of crushing rolls comprising an upper roll 57 and a lower roll 58. Each of these rolls is provided, at each end thereof, with a bearing ring or rail 59 which contacts the bearing rail of the other roll, positively limiting movement of the rolls toward each other, and the upper roll 57 is yieldingly urged toward the lower roll in a suitable known manner. In Figure 9 I have shown means 72, comprising a compression spring 73 and associated parts, similar to that of Patent No. 2,424,103, for yieldingly urging roll 57 toward roll 58. Any suitable known means may be employed for that purpose. The bite between the rolls 57 and 58 is somewhat less than the thickness of the package *p* so that, as the packages pass successively between the rolls 57 and 58, the enclosed tablets *t* are subjected to crushing pressure exerted through the top and bottom walls of the package, it being noted that the marginal portions 46 of the packages *p* are not acted upon by the crushing areas of the rolls 57 and 58, though the side marginal portions 46 of the packages are gripped between the bearing rails 59 for feeding the string of packages rearward between the rolls.

As the package *p* enters the bite of the rolls 57 and 58, crushing pressure on the packaged tablet is initiated at the center of the outer edge of leading portion *t*2 of the broken tablet, as will be understood more clearly from Figure 5,

in which the arrow *a* indicates the direction in which the package travels rearward between the crushing rolls, and the arrow *b* indicates the direction of travel of the crushing pressure exerted upon the tablet by the rolls 57 and 58. This crushing pressure travels from the central point of the outer edge of leading portion *t*2 of the broken tablet, and progresses across the latter to the central point of the outer edge of the following portion *t*1 of the broken tablet. As the package moves rearward between the rolls 57 and 58 and crushing of the tablet progresses, the space 55 between the portions *t*1 and *t*2 of the broken tablet accommodates a portion of the powder to which the leading portion *t*2 of the tablet is reduced by the crushing operation, and a certain amount of this powder is also accommodated by the space 45. Thereafter, the following portion *t*1 of the tablet is crushed and thereby reduced to a powder, sufficient of the resulting powder being accommodated by the space 45 and, to a certain extent, by the space 55, to prevent subjecting the container or envelope to injurious interior stresses. In that manner, rupture of or injury to the package *p* of a character to reduce its efficiency is guarded against.

The breaking of the packaged tablet into portions providing a space of considerable volume at the mid-portion of the package is of primary importance, in that it permits crushing of the tablets between the rolls 57 and 58 to reduce them to powder form, without danger of injury to the enclosing envelope or container. As has been noted above, the crushing action of the rolls 57 and 58 starts at one side of the tablet and progresses across the package to the other side of the tablet. The resultant powder is of appreciably greater volume than the tablet from which it has been produced. If the tablet were not broken preliminary to the crushing operation, in the manner described, the container would become completely filled with the powder in advance of the crushing rolls and, thereafter, as the package travelled between the rolls, there would result an advancing pressure wave transmitted through the powder and any remaining uncrushed portion of the tablet which would eventually exert high interior pressure on the package with resultant rupture or other serious injury thereto rendering the package unfit for use or greatly reducing its efficiency. In theory that difficulty could be avoided by materially increasing the space within the envelope about the tablet. In practice, however, that would not be practicable for several reasons. The resulting package would be objectionably large and bulky, which would be objectionable for obvious reasons. Further, if the space about the packaged tablet were materially increased, there would be objectionable slack in the package during the crushing operation, such that the walls of the package would be apt to be wrinkled and sharply creased, resulting in injury to the covering of the package to such an extent as to reduce materially its efficiency. By breaking the tablet into portions and separating these portions within the package so as to provide, at the central area thereof, a space of appreciable volume, I render it possible to crush the packaged tablet between the rolls 57 and 58 without risk of injury to the package, in the manner above described. That also renders possible a package of materially smaller size, for a given amount of powdered material, than could otherwise be produced while maintaining the full efficiency of the package with respect to its pro-

tective qualities. During the breaking operation a certain amount of the tablet may be crushed into powder form, and the leading portion *t*2 of the tablet may be broken into two or more parts or pieces, as may be following portion *t*1. In general, however, the tablet is broken into the two portions *t*1 and *t*2, spaced apart, as above described and as shown in Figure 5.

In reducing the packaged tablet to powder form, and reducing the powder to the desired degree of fineness, it is important in the first instance that the tablet be crushed so as to be reduced in its entirety to powder without subjecting the package to injurious interior pressure and without completely filling the space within the container. That I accomplish in the manner above stated, the space between the rolls 57 and 58 being such that after the package *p* has passed between these rolls there is still available within the package space to accommodate increase in volume of the powder due to crushing thereof. The further crushing operation is performed by a second pair of crushing rolls, comprising an upper roll 60 and a lower roll 61, provided at their ends with cooperating bearing rails 62 for positively limiting movement together of the rolls 60 and 61, while also feeding the string of tablets rearward between these rolls. The rolls 60 and 61 are so set that the bite therebetween is somewhat less than the bite between the rolls 57 and 58, so that as the packages *p*1, containing the powder produced by crushing of the tablets by the rolls 57 and 58, pass between the rolls 60 and 61 the powder in such packages is subjected to a crushing operation and is thereby increased in fineness and in volume. During the crushing operation between the rolls 60 and 61 the powder readily flows from between the bite of the rolls into the surrounding available space 45 within the package, thus avoiding subjecting the latter to objectionably high interior pressure. If desired, the packages *p*2, travelling rearward from between the rolls 60 and 61, may be subjected to further crushing operations by additional pairs of crushing rolls, with proper regard to avoiding injuriously high interior pressure within the packages, though I find that by subjecting the packages *p*1, or, more properly the powder within such packages, to a single crushing operation between the rolls 60 and 61, properly adjusted to reduce the powder to such a degree of fineness as substantially to fill the containers without subjecting them to objectionably high interior pressure, suffices for all practical purposes. The powder produced by passing the packages between the rolls 60 and 61 is materially finer than the powder produced by crushing of the tablets between the rolls 57 and 58, and will dissolve more readily in water or other suitable solvent than the powder resulting from the first crushing operation.

From the crushing rolls 60 and 61 the string of packages *p*2 is fed rearward between a pair of cutting rolls comprising an upper knife roll 64 and a lower platen roll 65. These rolls are provided at their ends with bearing rails 66 for positively spacing them apart, roll 64 being yieldingly urged toward roll 65 in a suitable known manner, and for gripping between them the lateral portions of the string of tablets and feeding the latter rearward between the cutting rolls. Roll 64 is provided with blades 67 mounted therein in a suitable manner, these blades cooperating with bars 68 of roll 65 for cutting the string of packages midway between adjacent ones thereof,

thus producing the completed individual packages p^3 . The packages p^3 may be discharged from the cutting rolls into a suitable container, or onto a suitable conveyor for transferring them to any other suitable location for packing, either by hand or by machine, for shipment. One of the completed packages p^3 is shown in Figures 6 and 7. It will be noted that this package is substantially completely filled with the powdered material, which is of appreciably greater volume than the same amount of the material in its tableted form shown in Figures 2 and 3, and that the side walls of the package are rounded, instead of being straight and outwardly converging as in Figure 3. In this package the powder is enclosed by an inner container comprising the strips 23 and 18 of regenerated cellulose or other suitable material, and an outer container or coating of metal foil comprising the strips 33 and 36, the package as a whole being moisture and air proof and capable of guarding the contained powder against deterioration indefinitely under unfavorable conditions. Packages of powdered coffee extract, prepared as above, have been tested at temperatures of 120° F. and moisture of 100% humidity, without any deterioration in the powder. While I have described my invention as applied to the packaging of coffee extract in powdered form, it may be used to advantage for packaging in powdered form numerous other substances, as will be understood. Also, where it is important that the packaged powder be protected from both air and moisture, particularly where the material is intended for use in climates having high temperatures and high humidity, both the inner covering, of regenerated cellulose or other suitable material, and the outer covering, of metal foil or analogous material, are used. In cases where the outer foil covering is not required, it may be omitted, and in cases where the inner covering of regenerated cellulose is not required it may be omitted, the powder then being enclosed within a container or envelope of metal foil or analogous material only. Briefly, within the broader concept of my invention, the powder may be contained within a package or envelope of metal foil only, or of regenerated cellulose only, or of both, depending upon requirements.

Preferably, the packaging means employed in practicing my invention is a packaging machine similar to that disclosed in the copending application of Frederick A. Lobleby, Walter E. Lowell, and William T. Williams, for Packaging machine, filed October 16, 1943, Serial No. 506,562, now Patent No. 2,424,103. In that machine, in order to package the tablets between the strips of regenerated cellulose only, the upper roll 41 of the second set of sealing rolls is supported in a raised or inoperative position, and the metal foil strips 33 and 36 are not delivered from the rolls 34 and 37, respectively, thereof. When it is desired to package the tablets in metal foil only, the rolls 19 and 24 of the cellulose strips 18 and 23, respectively, are replaced by rolls of metal foil from which the metal foil strips are fed about the rollers 22 and 26, and thence rearward between the pairs of rolls, the upper sealing roll 41 of the second pair of sealing rolls remaining in its raised or inoperative position. It is to be understood, however, that within the broader concept of my invention, any other suitable packaging means or machine may be used. While the material to be packaged preferably is initially formed into disc-like tablets having flat top and

bottom sides, it may be formed into tablets of any other suitable shape within the broader aspects of my invention. Also, I contemplate within my invention packaging the tablets in rows of two or more individual packages extending lengthwise of the enclosing strips, the latter, of course, being of appropriate width for that purpose, and, if desired, two or more tablets may be enclosed within a single package in alignment therein, these tablets being broken within the package or container and the portions of the broken tablets separated preliminary to the first crushing operation, in the manner above described.

15 As above indicated, and as will be understood by those skilled in the art, numerous changes may be resorted to in carrying out my invention, and I intend to include all such variations, as fall within the scope of the appended claims, in this 20 application in which the preferred form only of my invention has been disclosed.

I claim:

1. In means for reducing to powder form tablets sealed between strips of protective material 25 providing a continuous string of spaced packaged tablets enclosed in individual envelopes with the marginal portions of the strips extending a substantial distance outward beyond the envelopes, a pair of breaking rolls of a length to receive said 30 string between them, means in advance of said rolls effective for gripping the marginal portions of said strips and thereby controlling the speed of travel of said string to said breaking rolls, and a pair of crushing rolls in back of and parallel with 35 said breaking rolls, of a width to receive said string between them, said crushing rolls being yieldingly urged one toward the other and having end rails adapted and disposed to receive and frictionally grip between them the marginal portions 40 of said strip effective for moving said string rearward from said breaking rolls.

2. In means for reducing to powder form tablets sealed between strips of protective material providing a continuous string of spaced packaged 45 tablets enclosed in individual envelopes with the marginal portions of the strips extending a substantial distance outward beyond the envelopes, a pair of breaking rolls of a length to receive said string between them, means in advance of said rolls effective for gripping the marginal portions of said strips and thereby controlling the speed of travel of said string to said breaking rolls, the latter rolls being yieldingly urged one toward the other and having end rails adapted 55 and disposed to receive and frictionally grip between them the marginal portions of said strip effective for moving said string under tension from said gripping means through said breaking rolls, and a pair of crushing rolls in back of and parallel with said breaking rolls of a width to receive said string between them having end rails adapted and disposed to receive and frictionally grip between them the marginal portions of said strip effective for moving said string rearward 60 from said breaking rolls.

3. In means for producing separate packages of material in powdered form from tablets sealed between strips of protective material providing a continuous string of spaced packaged tablets enclosed in individual envelopes with the marginal portions of the strips extending a substantial distance outward beyond the envelopes at the sides thereof, a pair of breaking rolls adapted to receive the string between them and having end rails adapted and disposed to receive and

frictionally grip between them the marginal portions of said strips, means in advance of said rolls effective for positively gripping the marginal portions of said strips and thereby controlling the speed of travel of said string to said breaking rolls, a pair of crushing rolls in back of and parallel with said breaking rolls adapted to receive the string between them and having end rails adapted and disposed to receive and frictionally grip between them the marginal portions of said strips, and a pair of cutting rolls in back of and parallel with said crushing rolls having means for severing the strip between the envelopes, said cutting rolls having end rails adapted and disposed to receive and frictionally grip between them the marginal portions of the strips for advancing the string between said cutting rolls during the cutting operation.

4. In means for reducing to powder form tablets disposed between two strips of protective material stretched over the tablets and sealed together about and between them providing a continuous string of spaced packaged tablets enclosed in individual envelopes, a pair of breaking rolls, a pair of crushing rolls parallel with said breaking rolls, and means for continuously feeding the string of packaged tablets to said breaking rolls and thence to said crushing rolls, said breaking rolls having cooperating opposed lengthwise breaking bars disposed to engage the respective packaged tablets at the central areas thereof as they pass between said breaking rolls, the respective breaking bars having a breaking portion of a length to extend the full width of the packaged tablet, said breaking portion being of approximately triangular cross section with its following face substantially radial to the associated roll and its leading face inclined outwardly of the roll toward said following face.

5. The method of packaging material in powder form, which comprises providing a string of packaged tablets in individual envelopes stretched over and sealed about the respective

tablets with continuous marginal elements connecting the envelopes together and extending outward from the opposite sides thereof, continuously advancing said string by means of said marginal elements between breaking means effective for breaking the respective tablets apart centrally, thence through crushing means effective for crushing the broken tablets to powder form, and from the crushing means through cutting means effective for cutting the envelopes apart.

6. The method of packaging material in powder form, which comprises providing a string of packaged tablets in individual envelopes stretched over and sealed about the respective tablets with continuous marginal elements connecting the envelopes together and extending outward from the opposite sides thereof, continuously advancing said string by means of said marginal elements, breaking the respective tablets centrally along a line transverse to the direction of travel of the string and spreading apart the portions of the broken tablet during advancement of the string, crushing the broken tablets to powder form in the continued advancement of the string, and cutting the envelopes apart in the further continued advancement of the string.

FREDERICK A. LOBLEY.
